CLAIM

The ornamental design for a hydration belt, as shown and described.

DESCRIPTION

FIG. 1 is a front perspective view of a hydration belt. FIG. 2 is an alternative front perspective view of a hydration belt with lines illustrating environmental structure omitted. FIG. 3 is a front view of a hydration belt. FIG. 4 is a rear view of a hydration belt. FIG. 5 is a left side view of a hydration belt. FIG. 6 is a right side view of a hydration belt. FIG. 7 is a top view of a hydration belt; and, FIG. 8 is a bottom view of a hydration belt. The broken lines shown in the drawings are included for the purpose of illustrating environmental structure and form no part of the claimed design.
